CONICAL CUP AND ICE CREAM RECEPTACLE

Method Merta, Chicago, Ill.

Application October 8, 1936, Serial No. 104,677

5 Claims. (Cl. 229—1.5)

This invention relates to flexible, non-rigid receptacles, or cups adapted for any one of a number of commercial uses, and particularly adaptable as a receptacle and retainer for a semi-solid product such as ice cream, confections or like edible compositions. My invention relates also to the blank from which said receptacles are formed, the method of forming the same, as well as the finished article. My invention contemplates and includes an improved blank and paper receptacle construction which, when formed, is conical in cross section, more durable in use, self-locking, quickly and easily formed and which is possessed of a desirable degree of flexibility to permit the complete receptacle to be made without adhesive and to cause it to be satisfactory for use as a cup or a cup liner for retention of liquids.

Blanks for producing cups of my novel construction are cut from paper sheets either plain surfaced or having water-proofed coatings or qualities, after which the novel blank of my invention is rolled or bent about a suitable conical or substantially conical form so that one lateral edge of the cup forms an outer overlapping edge, and the opposite lateral edge of the blank and adjacent area become the overlapped edge, the two overlapping areas being held in close proximity to each other by the tendency of the paper blank to spread out to its original flat form. Further locking means comprises the locking engagement by insertion of a projecting tongue portion of the blank in a properly positioned slit and by additional interlocking engagement between suitably formed projecting members forming part of the cup blank one of which is substantially adjacent the upper periphery of the completed cup.

One object of the present invention is to provide a new and novel design of blank of paper or the like which has a plurality of peripheral tongues adapted to interengage or interlock in the formation of the cup, and which blank is of an outline permitting reversal of the blank so that it may be rolled and formed to present either one of the flat surfaces as the exterior of the cup.

A further object of my invention is the provision of a paper receptacle of conical cross section of economical manufacture, capable, compact nesting positions, and non-leakable, all without the use of adhesive to hold the same in formed position, and adapted for use particularly with semi-solid products such as ice cream, and which may be easily gripped and removed from the semi-solid body which it normally maintains.

A still further important object of my invention is the provision of a blank adapted to be formed into a paper receptacle adapted for use either as a cup liner or as a receptacle *per se* having no adhered areas, and having a plurality of integral projections at and adjacent its peripheral edges which are adapted to interlock and thereby provide means for releasably retaining the cup in its conical formed position.

It is a further object of this invention to provide a blank, capable of being formed into a conical receptacle, having a pair of curved edges forming a peripheral re-entrant angle and having a relatively long arcuate edge and a transversely extended slit at a point near the center of the blank for receiving a projecting tongue formed integrally with the blank edge.

A still further object of my invention is a provision of a flexible blank of paper or the like adapted to be formed into a paper receptacle of triangular cross section having a radially extending recess formed adjacent one end of a relatively long arcuate edge and a projecting tongue at the opposite end of said arcuate edge adapted to interlock with said recess in the formation of said cup.

Other and still further objects of my invention will be apparent from the disclosures of the accompanying drawing and description.

The invention (in a preferred form) is illustrated in the drawing and hereinafter more fully described.

Fig. 1 is a plan view of the novel blank of my invention.

Fig. 2 is a perspective view of a completed receptacle formed from the blank of Fig. 1.

Fig. 3 is a top plan view, looking from above, of the receptacle in assembled position.

Fig. 4 is a fragmentary side elevation showing the apex portion of the cup in partially assembled position just prior to insertion of the extending tongue.

Referring to the blank of Fig. 1, which is preferably made of paper, and which figure merely illustrates the preferred form of my invention, reference numeral 10 indicates generally the blank *per se*, which is preferably made of suitable paper, which has been coated or impregnated either during or subsequent to its manufacture with any one of a number of water-repellent compositions such as paraffin or the like to make said paper substantially impervious to water and to give it the proper degree of stiffness and rigidity.

The blank 10 has an arcuate edge 11, which

in the preferred form illustrated is of an approximate length of one-fourth of a circle. An angular slit or recess 12 is formed at a point a short distance from the right hand end of arcuate edge 11 and preferably in a direction parallel to the radial line of said arc. It will be noted that the slit or recess 12 has a rounded opening to provide for convenient insertion thereinto of an integral tongue of said blank hereinafter described. The rounded edge on the right of said slit 12, designated by reference numeral 11a merges and terminates in a non-radial, straight converging edge 13 as indicated. The end of the blank 10 at the opposite end of arcuate edge 11 has formed integrally therewith an extending and projecting tongue or extension 14, the projecting edge of which is preferably, though not necessarily substantially semi-circular which semi-circular edge terminates in an acute-angled recess 15 formed at the juncture of the edge of said tongue 14 and a non-radial converging edge 16. Edge 16 may be in an irregular line, and while illustrated as slightly curved inwardly, may be straight or otherwise. The lower end of 25 the non-radial converging side edge 16 terminates and merges with the annular edge of an integral extension or tongue 17 which is preferably formed so that it extends in a transverse or substantially horizontal and slightly downward direction when the blank is substantially in the position shown in Fig. 1. The lower edge 17a which defines the lower portion of the extension or tongue 17 and also a portion of blank 10, is arcuate as indicated and merges with the curved edge 18 in forming the re-entrant angle 19 at such juncture. The inwardly curved edge 18 forms a lower extended portion of the straight side edge 13 as shown in the drawing. It will be noted that the portion of the blank immediately adjacent the curved edge 18 and exteriorly of a chord drawn from the apex of re-entrant angle 19 also forms an extension or gripping portion designated by reference numeral 20 which facilitates the formation of the blank 45 into a cup or receptacle and provides convenient means whereby the paper blank may be gripped by suitable mandrel and rolled into conical form.

In the formation of the cup, the mandrel (not shown) which is of frusto-conical form with a movable gripping element representing a portion of its tip, is adapted to grip the extension 20 so that the only gripped portion of the blank will be that exterior of the chord illustrated in dotted lines in Fig. 1. Thereupon, the extending tongue 20 is folded along the line defining a chord which is shown in dotted lines in Fig. 1, and thereupon the mandrel is rotated and the cup rolled and wrapped about its conical surface in an arcuate path beginning at said extension 20 and until said blank 10 is nearly flat on the mandrel and the opposite edge 16 and tongues 14 and 17 are substantially in overlapping adjacent positions.

As clearly indicated in the drawing, a longitudinally and transversely extending slit 21 is formed substantially midway between tongue 14 and slit 12 and at a point above re-entrant angle 19 about one-third of the distance from said angle 19 to arcuate edge 11. When the blank 70 10 is in the rolled position on the mandrel as heretofore described, the areas adjacent the non-radial side edges 13 and 16 are overlapped, as clearly shown in dotted lines in Fig. 3, and the blank areas adjacent the gripping extension 20 form the interior reenforcing portion for the

apex of the cup, as clearly indicated in Fig. 3. The first step which is carried out to secure the conical receptacle in proper form and in a position shown in Fig. 2 is to insert the extending tongue 14 through slit 12 which it overlies in 5 said position, said insertion movement being toward the interior of the cup, whereupon the lower arcuate edge of tongue 14 and recess 15 will impinge and interlock in the slit 12 thereby holding said tongue 14 in the locked position illustrated in Fig. 2. The lower exterior overlapping portions of the blank 10, when in the rolled position for assembly as described, are secured and held in place against an exterior surface of the blank areas adjacent side edge 13 and 15 extension 20 by means of interlocking engagement of extending tongue 17 and the relatively narrow slit 21.

When the blank has been rolled to the assembling position as before described, the extending tongue 17 is inserted, either mechanically or otherwise, into slit 21, said slit 21 being of a length so that tongue 17 fits tightly therein, and when inserted, the edges of said slit will impinge upon the surfaces of tongue 17 and frictionally retain the same therein. As shown in Fig. 2, the inserted tongue 17 is shown in dotted lines on the inside of the cup. The position of the rolled blank just prior to the insertion of the extending tongue 17 is shown in side elevation in Fig. 4, which Fig. 4 also shows the shape of the slit and its converging side edges.

Fig. 3 shows a view taken from the top, and particularly clarifies the areas of the cup blank adjacent edge 13 which are overlapped by the 35 opposite lateral side portions thereof. As indicated, the extending tongue 17 projects interiorly from slit 21 and extending tongue 14 and is in inter-engaging position with the slit 12, thereby holding the receptacle or cup firmly in assembled rigid position.

Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

1. A conical receptacle formed from a blank having a central slot and an arcuate edge, two opposed converging side edges extending from said arcuate edge, a pair of spaced apart projecting tongues formed integral with one of said side edges, the lower portions of said side edges merging in a reentrant angle whose apex is the axis of said arcuate edge, said arcuate edge having a slit therein.

2. A blank having an arcuate edge having a slit opening in said arcuate edge, two converging side edges, one of said side edges having two spaced apart integral transversely extending tongues, said side edges merging in a curved re-entrant angle whose apex is at the axis of said arcuate edge, said blank having a central slit adapted to receive the lower of said transversely extending tongues.

3. A blank for a cup of substantially conical 70 form having a substantially central slit, having an upper arcuate edge, a pair of opposite side edges converging from said arcuate edge to each other, the lower edges of said blank defining adjacent arcs forming an angle and a grippable ex- 75

tension on one side of said angle, and forming an integral projecting tongue on the other side of said angle adapted to be inserted in said central slit.

- 5 4. A receptacle of paper or the like of triangular cross section and of substantially conical form and formed from a single blank whose opposite side edges are overlapped, the periphery of said receptacle having a slit and a spaced apart tongue extending from one side edge inserted therein for holding said receptacle in rolled position, said blank having a substantially central
- 10

slit, said cup having an integral lower tongue extending from one of said overlapped edges and inserted in said central slit.

5 5. A cup of triangular central cross section and of conical shape formed of a single blank having its opposite side edges overlapped and held together by inter-engagement of a tongue and slit on opposite sides respectively of said blank, and having a lower integral tongue, said lower tongue being inserted in a slot below the periphery of 10 said cup.
